CLAIM

The ornamental design for a pallet portion of candle holder, as shown and described.

DESCRIPTION

FIG. 1 is a perspective view of a pallet portion of a candle holder showing my new design;

FIG. 2 is a front view in elevation thereof;

FIG. 3 is a rear view thereof;

FIG. 4 is a right side view in elevation thereof;

FIG. 5 is a left side view in elevation thereof;

FIG. 6 is a top view thereof; and,

FIG. 7 is a bottom view thereof.

The dashed lines are environmental only and form no part of the claimed design.
